UNITED STATES PATENT OFFICE.

GEORGE C. McCARRON, OF KANSAS CITY, MISSOURI.

DESIGN FOR A BADGE.

Application filed September 19, 1925. Serial No. 14,834. Term of patent 14 years.

To all whom it may concern:

Be it known that I, GEORGE C. McCARRON, a citizen of the United States of America, residing at Kansas City, in the county of Jackson and State of Missouri, have invented a new, original, and ornamental Design for a Badge, of which the following is a specification, reference being had to the accompanying drawing, forming a part hereof.

In the drawing:

Fig. 2 is an edge view of the same.

I claim:

The ornamental design for a badge, as shown.

GEORGE C. McCARRON. [L.S.]
